E. KRONMAN

STERILIZING AND WATER HEATING DEVICE

Filed April 4, 1923

Inventor:
Edward Kronman,
By his Attorney,
Geo. F. Miatto

Patented Sept. 9, 1924.

1,508,187

UNITED STATES PATENT OFFICE.

EDWARD KRONMAN, OF NEW YORK, N. Y.

STERILIZING AND WATER-HEATING DEVICE.

Application filed April 4, 1923. Serial No. 629,804.

To all whom it may concern:

Be it known that I, EDWARD KRONMAN, a citizen of the United States, and a resident of the borough of Manhattan, city, county, and State of New York, have invented certain new and useful Improvements in Sterilizing and Water-Heating Devices, of which the following is a specification sufficient to enable those skilled in the art to which the invention appertains to utilize the same.

My improvements relate to sterilizing and water heating apparatus generally, but more particularly to the type of such apparatus designed for use in barber shops, hospitals, and other places in which a continuous supply of hot water for shaving, washing, and analogous purposes is desirable, in conjunction with means for effecting the sterilizing of large quantities of towels, napkins and the like for sanitary reasons. The object of my invention is the production of a comparatively simple and inexpensive unitary device of the character designated, of maximum capacity and efficiency, in which the hot water tank, steam generator, and sterilizing chamber are detachably mounted one above the other in such manner as to facilitate inspection, cleaning, and so forth; in which the water in the steam generator is heated by means of one or more drop tubes positioned in flues passing through the hot water tank; in which provision is made for feeding the steam generator, as required, with hot water direct from the heating tank, etc., all as hereinafter fully and specifically described and claimed.

In the accompanying drawings I exemplify a practical embodiment of the essential features of my invention in a sterilizing and water heating device of unitary character, although I do not limit myself to the identical form and construction of parts shown since changes may be made in minor details and modifications resorted to without departing from the spirit and intent of my invention in this respect.

With this understanding,

Fig. 1, represents what may be designated as a front elevation of my improved sterilizing and water heating apparatus;

Fig. 2, is an elevation of the sterilizing chamber removed from the top of the steam generator;

Fig. 3, is a central vertical sectional elevation of the parts shown in Fig. 1;

Fig. 4, is a horizontal section taken upon plane of line 4—4, Fig. 3;

Fig. 5, is an elevation of the steam generator section, detached;

Fig. 6, is a horizontal section taken upon plane of line 6—6, Fig. 3.

The tank section T, preferably cylindrical in shape, is removably supported on a basic standard B, of any suitable or desired configuration, having inlets b, b, in its upper portion for the admission of air to the heating chamber t, in the lower part of said tank T, in which the heating element H, is positioned,—said heating element consisting of a gas burner or equivalent means of raising the temperature.

Above the heating chamber t, is formed with a diaphragm t', the space t* between which and the upper diaphragm t', constitutes the main water chamber or tank proper, supplied through the inlet t³, with water under service pressure,—t⁴, being the outlet for the supply of hot water for various extraneous uses, and the outlet t⁴, being provided with a valve t⁴', for the control of the flow. By placing the inlet t³, at the upper part of the water chamber t*, and the outlet t⁴, at the lower portion thereof, I insure a uniform temperature of water within said water chamber t*. 85

The steam generator G, rests upon the top of the tank section T, and may be supplied with hot water therefrom through the medium of the pipes p, p, controlled by the valve p'. The sterilizing chamber S, in turn rests upon the said steam generator G, being formed with a neck s, fitting in an opening formed for the purpose in the upper portion of said steam generating chamber S, as shown more particularly in Fig. 3 95 of the drawings, said sterilizing chamber S, being also formed with a drainage floor s', for the support of towels, etc., to be steamed, and with the usual door s², in a manner at present well known in the art. 100

The water in the steam generator G, is heated through the medium of drop tubes g, g, which protrude into flues t⁵, t⁵, extending vertically through the water space t*, in the tank T, and through which the heated air and products of combustion (if any) pass from the heating chamber t, to the compartment x, between the upper diaphragm t², of the tank T, and the bottom of said steam generator, as shown more par 105 110

ticularly in Fig. 3, of the drawings,—the heated air, etc., escaping eventually through outlets α' , formed for the purpose in the side walls of said compartment α .

5 The drop tubes g , g , are of course closed at their lower extremities, their upper extremities opening into the steam generating chamber G , of which they practically form a part.

10 Any desired plural number of these drop tubes g , g , may be provided, suitably spaced apart; and in order to facilitate removal of sediment each tube may be provided with a drainage pipe g' , as shown in connection 15 with the central drop tube g , shown in the drawings,—said drainage pipe g' , extending through the heating chamber t , and being provided with an external pet cock g^2 . In order to facilitate the disconnection of 20 this drain pipe g' , when it is desired to remove the steam generator G , from the tank, the inner end of said pipe g' , is male screw threaded for engagement with an internally threaded union g^3 , on the bottom of the 25 said drop tube g . A union p^2 , may be provided in the pipe connections p , p , between the tank T , and the steam generator G , to facilitate disconnection between said parts when desired.

30 My specific construction and arrangement of parts is simple and effective,—the heat being utilized to the fullest extent. Furthermore, the whole apparatus may be quickly taken apart for cleaning, repairs, 35 etc.; and externally is of compact symmetrical appearance.

What I claim as my invention and desire to secure by Letters Patent is,

1. In sterilizing and water heating apparatus of the character designated, the combination of a water tank, means thereunder 40 for heating same, said tank being formed with a flue for the passage of the hot air,

etc., and a steam generator superposed on said water tank and formed with a drop tube 45 extending into said flue in the water tank, said drop tube being closed except at the top and the latter opening into said generator, together with a sterilizing chamber mounted on said steam generator, substantially 50 in the manner and for the purpose described.

2. In sterilizing and water heating apparatus of the character designated, the combination of a water tank, means thereunder 55 for heating same, said tank being formed with a flue for the passage of the hot air, etc., and a steam generator superposed on said water tank and formed with a drop tube 60 extending into said flue in the water tank, said drop tube being closed except at the top and the latter opening into said generator, said drop tube being provided with a drain tube and pet cock, together with a sterilizing chamber mounted on said 65 steam generator, substantially in the manner and for the purpose set forth.

3. In sterilizing and water heating apparatus of the character designated, the combination of a water tank, means thereunder 70 for heating the same, said tank being formed with a plurality of flues for the passage of hot air, etc., and a steam generator superposed on said water tank and formed with a plurality of drop tubes 75 extending each into one of the said flues in the water tank, said drop tubes being closed except at the top and the latter opening into said generator, together with a sterilizing chamber mounted on said steam generator, substantially 80 in the manner and for the purpose set forth.

EDWARD KRONMAN.
